(57) **CLAIM**

The ornamental design for a plastic side dish container comprising a faceted bowl with a lid, as shown and described.

DESCRIPTION

FIG. 1 is a perspective view of a plastic side dish container comprising a faceted bowl with a lid depicting a first embodiment of our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;
FIG. 7 is a bottom plan view thereof;
FIG. 8 is an exploded perspective view thereof, with the lid detached from the bowl for clarity of illustration;
FIG. 9 is top plan view of the lid thereof, shown in isolation for clarity of illustration;
FIG. 10 is a bottom plan view thereof;
FIG. 11 is a front elevation view thereof;
FIG. 12 is a rear elevation view thereof;
FIG. 13 is a left side elevation view thereof;
FIG. 14 is a right side elevation view thereof;
FIG. 15 is a top plan view of the bowl thereof, shown in isolation for clarity of illustration;
FIG. 16 is a bottom plan view thereof;
FIG. 17 is a front elevation view thereof;
FIG. 18 is a rear elevation view thereof;
FIG. 19 is a left side elevation view thereof; and
FIG. 20 is a right side elevation view thereof.
FIG. 21 is a perspective view of a plastic side dish container comprising a faceted bowl with a lid depicting a second embodiment of our new design;
FIG. 22 is a front elevation view thereof;
FIG. 23 is a rear elevation view thereof;
FIG. 24 is a left side elevation view thereof;
FIG. 25 is a right side elevation view thereof;
FIG. 26 is a top plan view thereof;
FIG. 27 is a bottom plan view thereof;
FIG. 28 is an exploded perspective view thereof, with the lid detached from the bowl for clarity of illustration;
FIG. 29 is top plan view of the lid thereof, shown in isolation for clarity of illustration;
FIG. 30 is a bottom plan view thereof;
FIG. 31 is a front elevation view thereof;
FIG. 32 is a rear elevation view thereof;
FIG. 33 is a left side elevation view thereof;
FIG. 34 is a right side elevation view of the lid thereof;
FIG. 35 is a top plan view of the bowl thereof, shown in isolation for clarity of illustration;
FIG. 36 is a bottom plan view thereof;
FIG. 37 is a front elevation view thereof;
FIG. 38 is a rear elevation view thereof;
FIG. 39 is a left side elevation view thereof; and
FIG. 40 is a right side elevation view thereof.
The broken line portion of the figure drawings is included to show unclaimed subject matter only and forms no part of the claimed design.
